(57) **CLAIM**

The ornamental design for a packing box, as shown and
described.

DESCRIPTION

FIG. 1 is a perspective view of a packing box in the closed
configuration showing my new design.

FIG. 2 is a top view of the packing box in the closed
configuration showing my new design.

FIG. 3 is a first side view of the packing box in the closed
configuration showing my new design.

FIG. 4 is a bottom view of the packing box in the closed
configuration showing my new design.

FIG. 5 is a second side view of the packing box in the closed
configuration showing my new design.

FIG. 6 is a perspective view of the packing box in the open
configuration showing my new design.

FIG. 7 is a top view of the packing box in the open
configuration showing my new design.

FIG. 8 is a first side view of the packing box in the open
configuration showing my new design.

FIG. 9 is a front view of the packing box in the open
configuration showing my new design; and,

FIG. 10 is a back view of the packing box in the open
configuration showing my new design.
